UNITED STATES PATENT OFFICE.

GEORGE E. WOODBURY, OF CHARLOTTE, MICHIGAN.

DESIGN FOR A TRACE-HOLDER.

SPECIFICATION forming part of Design No. 35,665, dated February 4, 1902.

Application filed December 18, 1901. Serial No. 86,453. Term of patent 7 years.

To all whom it may concern:

Be it known that I, GEORGE E. WOODBURY, a citizen of the United States, residing at 321 Prairie street, Charlotte, in the county of Eaton and State of Michigan, have produced a new and original Design for a Trace-Holder, of which the following is a specification.

This invention relates to a new and original design for a trace-holder; and the essential features reside in the design as illustrated in the accompanying drawings, wherein--

Figure 1 is a perspective view of a trace-holder embodying the features of the design.

Fig. 2 is a horizontal section of the same.

Fig. 3 is a transverse vertical section of the holder disposed vertically to show the general U shape of the same.

The design is characterized by a U-shaped body 1, having curved edges 2 and reduced toward one end 3, the opposite end 4 being cut away in concave planes. Surrounding the body 1 and terminally merging into the latter are convex ribs or enlargements 5, openings 6 and 7 being formed at the opposite ends.

Having thus described the invention, what is claimed as new is--

The design for a trace-holder, as herein shown and described.

In testimony whereof I affix my signature in presence of two witnesses.

GEORGE E. WOODBURY.

Witnesses:

W. F. STIRLING,
SETH ROBINS.
